APPARATUS FOR MAINTAINING VEGETABLES AND THE LIKE IN FRESH CONDITION

Walter A. Reich, Kansas City, and Charles H. Smallwood, Brownington, Mo.; said Smallwood assignor to said Reich

Application March 22, 1935, Serial No. 12,412

15 Claims. (Cl. 211—127)

This invention relates to an apparatus for maintaining vegetables and the like in fresh condition and more particularly to an apparatus of that character for supporting and displaying vegetables and similar articles subject to dehydration when exposed to air, and has for its principal object to provide a support for said vegetables and the like wherein dehydration thereof is retarded and the articles are kept in fresh, crisp condition.

Other important objects of the invention are to provide a support with means for intermittently applying a mist over the articles supported, and to effect evaporation of the mist for reducing temperature of the articles and to prevent them from becoming water-logged.

In accomplishing these and other objects of the invention, as hereinafter pointed out, we have provided improved details of structure, the preferred form of which is illustrated in the accompanying drawings, wherein:

Fig. 1 is a perspective view of a support embodying the features of the present invention.

Fig. 2 is a vertical section through the longitudinal center of the support on the line 2—2, Fig. 5.

Fig. 3 is a horizontal section through the spray and air ducts, particularly illustrating the operating mechanism for reciprocating the ducts longitudinally of the support.

Fig. 4 is a similar section illustrating shift of the clutch to reverse movement of the carriage.

Fig. 5 is a vertical cross section through the support.

Fig. 6 is an enlarged detail section through the nozzle supporting carriage.

Fig. 7 is a detail section through one of the spray nozzles.

Fig. 8 is an enlarged section through the gear mechanism for reversing direction of movement of the carriage.

Referring more in detail to the drawings:

1 designates a frame including end members 2 and 3 each comprising vertical angle members 4 and 5 connected at their upper ends by a horizontal angle bar 6 and by end sheets 7. The lower ends of the angle members 4 and 5 are connected to the horizontal angle member 6 by angle braces 8 and 9. The frame members 2 and 3 are connected at their ends by side sheets 10 and 11 which cooperate with the end sheets 7 to form a rectangular housing of substantially counter height for supporting a plurality of rows of trays 12—13 and 14—15.

The end sheets 7 extend above the horizontal

angle members 6 and carry therebetween upwardly inclined plates 16 and 17 inset from upwardly inclined edges 18 and 19 of the sheets and which have their lower edges 20 interconnected with the upper edges of the sheets 10 and 11 by means of webs 21 to support the rows of trays 12 and 15. The upper edges of the plates 16 and 17 are flanged inwardly as at 22 and 23 to support the water catch pans 24 and 25 which slope downwardly toward the longitudinal center 10 of the housing and have upwardly turned flanges 26 and 27 spaced apart to form a passageway 28 therebetween for a purpose later described.

The opposite sides of the water pans 24 and 25 have upwardly inclined flanges 29 and 30 to cooperate with the web portions 21 and with the ends sheets to house the trays 12 and 15.

The opposite ends of the upper rows of trays 13 and 14 are supported on flanges 31 and 32 of longitudinal angle members 33 and 34 having their ends fixed to the extensions of the plates 7 at a higher elevation than the pans. The opposite flanges 35 and 36 of the angles extend upwardly to cooperate with the flanged ends of the plates 22 and 23 to prevent shifting movement of the trays.

The trays are thus supported in inclined position with the trays 12 and 15 at a greater angle of inclination than the trays 13 and 14 in order to support and display vegetables and the like that may be inserted into the respective trays.

The angles 33 and 34 are spaced apart to provide a passageway 37 therebetween which cooperates with the passageway 28 for reciprocatory travel therethrough of air and spray nozzle conduits 38 and 39 that are moved longitudinally of the rack by means of a carriage 40 as later described.

In supports of this character wherein vegetables and other articles are exposed to the air, the vegetables are constantly subject to dehydration which not only affects their salability, but also results in loss to the merchant because of shrinkage due to the loss of the moisture content. It has been found that to prevent excessive evaporation of the moisture content, the vegetables may be wetted by applying a mist like spray.

While the spray prevents dehydration of the vegetables, it has the disadvantage in that it causes them to become water-logged and injures their salability to as great an extent as that due to their loss of moisture.

It is, therefore, an object of the present invention, as above pointed out, to provide means for intermittently subjecting the vegetables to

a spray and to effect evaporation of the moisture, thereby preventing the vegetables from becoming water-logged, reducing the temperature thereof, and retaining them in a better state of preservation, as now to be described.

Extending longitudinally of the rack in laterally offset relation with the passageways 28 are channel shaped track members 41 and 42 having their ends fixed to and supported upon the angle members 6. The channels are arranged on edge with their flanges 43 and 44 in facing relation as best illustrated in Figs. 5 and 6 to form upper and lower track surfaces for guidingly supporting the carriage 40.

15 The carriage 40 includes a primary frame 45 including longitudinal angles 46 and 47 connected at their ends by cross bars 48 and 49 having their ends fixed to the horizontal flanges 50 of the longitudinal angles to form a rectangular shaped frame of slightly narrower width than the track spacing to mount a secondary frame 51. The secondary frame is inset in the primary frame and comprises longitudinal angles 52 and 53 of shorter length than the longitudinal angles 46 and 47 and which are arranged with their horizontal flanges 54 and 55 extending outwardly in the direction of the horizontal flanges of the angles 46 and 47.

30 The ends of the angles 52 and 53 are connected by a cross bar 56 and a plate 57 respectively that are welded or otherwise attached to the horizontal flanges 54 and 55. Rotatably mounted on suitable pins 58 and 59 at the respective ends of the angles 52 and 53 are pairs of rollers 60 and 61 having peripheral grooves 62 and 63 therein for respectively receiving the inwardly extending horizontal flanges of the longitudinal angles 46 and 47.

It is thus apparent that the secondary frame 40 is mounted for relative longitudinal movement within the primary frame, which relative movement forms an important part in reversing directional travel of the carriage as later described.

The ends of the primary carriage are supported upon pairs of rollers 64 and 65 operably engaging between flanges of the track members 41 and 42 as best illustrated in Fig. 6.

In order to prevent lateral movement of the carriage relatively to the track members, the flanges thereof also carry guide rollers 66 and 67 arranged with their axes vertical so that the periphery thereof engages the inner faces of the webs 68 and 69 of the track members as shown in Fig. 6.

55 Carried on the horizontal flange of the angle member 46 of the primary frame is a motor 70 which drives a power shaft 71 through a reduction gearing 72 that is rigidly attached to the motor housing.

60 Located on the plate 57 is a gear housing 73 in which is rotatably mounted a pair of facing bevel gears 74 and 75. The gears 74 and 75 have hubs 76 and 77 which are mounted in the inner races of roller bearing sets 78 and 79 that are carried in recesses 80 and 81 in the respective ends of the housing in axial alignment with the shaft 71.

Extending slidably through a bearing opening 82 in the side of the housing and through the 70 hubs 76 and 77 of the gears is a shaft 83 having flexible connection 84 with the shaft 71. Extending through the shaft 83 intermediate the gears 74 and 75 is a pin or clutch member 85 to be selectively engaged with clutch faces 86 and 75 87 formed on the hubs of the bevel gears.

Meshing with the teeth of the gears 74 and 75 is a bevel gear 88 fixed to the end of a shaft 89 that is rotatably mounted in a bearing opening 90 formed in a cover plate 91 closing an open side of the housing 73. The opposite end of the 5 shaft projects through the plate and carries fixed thereto a sprocket wheel 92 operably engaging the links of a chain 93. The chain 93 extends longitudinally of the rack at a point intermediate the track members and has its ends 10 fixed to vertical flanges 94 and 95 of angle irons 96 and 97 extending across and fixed to the ends of the track members.

In order to increase the extent of driving contact of the sprocket with the chain, the plate 91 carries idler rollers 98 and 99 having their axes located in substantially horizontal alignment with the axis of the shaft 89 for engaging the under side of the chain while the teeth of the sprocket engage the upper side of the chain as 15 shown in Fig. 2.

It is thus apparent that when the motor is operated and the pin 85 is engaged with the bevel gear 74, the bevel gear 88 will be rotated in one direction to cause rolling movement of the 25 sprocket 92 on the chain 93 in one direction and when the pin is engaged with the bevel gear 75, the sprocket will rotate in reverse direction. I am, therefore, enabled to effect movement of the primary carriage longitudinally of the track 30 in either direction depending upon which of the bevelled gears is engaged with the pin.

With the construction thus far described, it is apparent that when the secondary frame which mounts the gear housing is moved to the right in 35 Fig. 3, the pin 85 will engage the bevel gear 75 and when the secondary carriage is moved in the opposite direction, the pin will engage the gear 74.

We, therefore, provide means for shifting the secondary frame relatively to the primary frame 40 when the carriage reaches the respective ends of the track member.

This is accomplished by providing the primary frame with a shift rod 100 having its ends mounted in angle brackets 101 and 102 carried by the 45 end cross members of the primary frame and which is yieldingly retained so that the ends of the shift rod project equal distances from the bearing brackets by springs 103 and 104 coiled about the ends of the shaft and having one of 50 their ends bearing against the brackets and their other ends anchored to the shaft by pins 105.

Threaded into the ends of the shift rod are adjusting screws 106 and 107 having heads 108 adapted to respectively engage against the vertical flanges of the angle members 96 and 97 55 when the carriage reaches the respective ends of the track. The screws 106 and 107 are held in adjusted position relatively to the rod by lock nuts 109 threaded thereon and engaging the ends 60 of the rod.

Assuming that the carriage is moving in the direction of the angle 47, the head of the adjusting screw 107 engages against the vertical flange of the angle 97. The movement of the carriage is 65 yieldingly stopped due to the spring 103. However, since the pin 85 is still in engagement with the gear 75, the sprocket will continue its movement along the chain 93 which causes slight shifting movement of the secondary carriage relatively to the primary carriage.

Since the motor is carried by the primary carriage, and the shaft 83 is fixed relatively to the motor, the gears 74 and 75 will shift to the right on the shaft 83 moving the pin out of engage- 75

ment with the gear 75 and cause its engagement with the gear 74. Immediately upon engagement of the pin with the gear 74, the sprocket 92 will be rotated in the opposite direction to reverse movement of the carriage. The carriage will then move along the track toward the left until the adjusting screw 106 engages the angle member 98, whereupon the primary frame is stopped, but the secondary carriage continues to have slight movement since the pin remains in engagement with the gear 74. However, its relative movement between the secondary and primary carriages causes the pin to disengage with the gear 74 and to reengage with the gear 75 to again reverse movement of the carriage.

It is thus obvious that the carriage will reciprocate back and forth upon the track carrying the spray and air nozzles now to be described.

Fixed to the longitudinal angle 46 of the primary carriage are L fittings 111 and 112 carrying laterally extending nipples 113 and 114 to which are connected L fittings 115 and 116. Screwed into the fittings 115 and 116 are vertical pipes 117 and 118 extending upwardly through the passageways to a point above the uppermost trays 13 and 14.

Fixed to the upper ends of the pipes are T fittings 119 and 120 carrying lateral branches 121 and 122, the lateral branches 121 and 122 constituting arms for supporting the ends of angles 123 and 124 which form a frame for supporting the spray mechanism now to be described.

Connected with the T fitting 120 is a nipple 125 carrying an L shaped fitting 126 which in turn carries a nipple 127 having a T fitting 128.

Screwed into the T fitting 128 are laterally directed pipes 129 and 130 having their ends terminating above the center of the upper rows of trays 13 and 14. The ends of the pipes are enclosed by plugs 131 and 132.

Formed in the lower peripheries of the pipe adjacent the ends thereof are port holes 133 forming jets through which the water is sprayed over the vegetables carried in the trays.

In order to adjust size of the spray, the pipes carry sleeves 134 and 135 having openings 136 adapted to be moved relatively to the openings 133 when the sleeves are rotated on the pipes. The sleeves preferably comprise bands having apertured ears 137 and 138 for mounting screws 134 by which the bands are tightened on the shaft when the apertures 136 are in adjusted position to the ports 133.

In order to spread the spray, the jets are discharged against plate members 140 and 141 carried in a pan 142 that is supported by the angle members 123 and 124 as best shown in Figs. 1 and 5.

The sprays upon impinging against the plates 60 are directed upwardly and outwardly from the sides of the pan in the form of a mist to settle upon the vegetables.

Water collecting in the pan passes off through a drain pipe 143 connected with a T 144 inserted in the vertical pipe 117 previously described and from where the water drains into one of the pans 24 and 25 through a T fitting 144 located in the vertical pipe below the T just described. In order to insure that the water is discharged into the pan, the outlet to the T is extended by a nipple 145.

Carried by the motor housing is a fan housing 146 in which is rotatably mounted a fan rotor 147 driven by an extended shaft of the motor. Connected to the outlet to the fan housing is a verti-

cal conduit 148 forming the air delivery nozzle 38, previously mentioned.

The conduit extends upwardly through the passageways and terminates slightly above the upper edges of the trays 13 and 14 where it is provided with laterally directed outlets 149 and 150 where-through air is delivered onto the upper surface of the vegetables in the trays.

In order to direct the air downwardly onto the vegetables, the upper end of the conduit carries 10 downwardly directed deflectors 151 and 152.

Formed in the conduit at a point above the water pans 24 and 25 which catch the water drippings from the vegetables in the trays 13 and 14 are outlets 153 and 154 for discharging jets of 15 air against the bottom of the vegetables to effect partial evaporation of the spray.

In order to frictionally latch the secondary frame with the primary frame, the primary carriage has a plate extending laterally from the angle to mount a pivoted lever 155 terminating in a hooked shaped end 156 to frictionally engage a lug 157 projecting laterally from the angle of the secondary frame. The lever arm is yieldingly retained in engagement with the lug by a 25 spring 158 coiled about a threaded stud 159 that extends through an opening 160 in the lever arm, one end of the spring engaging against the lever arm and the other against a wing nut 161 threaded on the end of the stud to adjust tension of the 30 spring. The hook shaped end of the lever arm is not such as to latchingly restrict movement of the secondary frame relatively to the primary frame, but is of such shape that the spring yieldingly retains the hook shaped end in engagement with 35 the lug and allows the lug to cam the lever arm outwardly against the pressure of the spring when the pin is shifted from one of the bevelled gears to the other.

In order to supply water to the pipe 118, the 40 L shaped fitting 112 is connected by a flexible conduit 162 leading from a suitable source of water supply not shown.

The pans 24 and 25 are drained by means of suitable drain pipes 163 and 164 connected to a 45 common pipe 165 leading to a sewer or other place of disposal, not shown.

While the spray may be operated continuously, we provide means operable incidental to shifting movement of the carriage frames for shutting off 50 the sprays when the carriage is moving in one direction across the support. This is accomplished by providing the pipe 114 with a valve 166 located in substantial alignment with the bar 56 of the secondary frame. The valve 166 has an actuating 55 stem 167 that extends into position for engaging a cam lug 168 on the bar 56 when the secondary carriage is shifted toward the left in reference to Fig. 3, so that when the carriage is moved to the left, the lug retains the stem in depressed condition to open the valve. When the carriage moves in the opposite direction and the inner frame shifts to the right, the cam lug 168 will move away from the stem to permit closing of the valve.

In order to confine the sprays, the angles 123 65 and 124 may carry a hood 169 that projects outwardly over the pan 142 as best illustrated in Fig. 5.

In operating an apparatus constructed and assembled as described, perishable vegetables, fruit 70 or similar articles are placed in the trays 13 and 14. The motor 70 is then energized to rotate the shaft 82 which drives one or the other of the bevel gears 74 or 75 through the pin 85 depending upon which one of the gears is engaged by the pin. 75

Assuming that the pin engages the clutch face of the gear 74 and assuming that the gear 74 rotates in an anti-clockwise direction relatively to the face thereof, the sprocket 92 will rotate in an anti-clockwise direction, Fig. 2, to cause movement of the carriage toward the left.

When the carriage is moving in this direction, the cam lug 168 is held in position to open the valve 166 so that water is delivered through the pipe 168 to the respective jets 133.

The volume of water admitted through the jet may be controlled by regulating the relative relation of the jet 133 with the port 136 in the sleeve 130. After the adjustment, the sleeve may be tightened to hold it in adjusted position by manipulating the screw 139.

The water is then discharged against the plates 140 and 141 from which it is deflected upwardly and outwardly to fall in a mist over the vegetables simultaneously with movement of the carriage.

When the carriage reaches the left hand side of the machine, Fig. 2, the set screw on the rod 100 will engage the flange 94 of the angle 96 to stop movement of the primary frame; however, due to the fact that the pin remains in engagement with the gear 74, the secondary carriage will continue movement in the same direction. However, shifting movement of the secondary carriage relatively to the primary carriage causes the pin to move out of engagement with the gear 74 and to engage with the gear 75.

This shifting movement is also supplemented by recoil of the compressed spring 104 to cause initial reverse movement of the primary frame.

35 This carries the pin past the dead center position between the gears and into positive engagement with the gears 75. When the pin engages the gear 75, the sprocket is rotated in reverse direction to move the carriage toward the right, Fig. 2.

40 As the carriage is moved to the right, the secondary frame shifts to the right relatively to the primary frame to allow closing of the valve 166 to shut off the spray; however, during movement of the carriage, the fan is operating to blow air 45 streams over and under the respective trays to cause evaporation of the water spray thereon. This drying effect of the air prevents the vegetables from becoming water-logged and also reduces their temperature incidental to the evaporation.

When the carriage comes to the opposite end of the support and the screw 107 engages the angle 97, the secondary carriage is caused to shift in the opposite direction relatively to the primary carriage to again reverse movement thereof.

55 From the foregoing, it is apparent that we have provided an apparatus for maintaining vegetables and the like in fresh, crisp condition to not only increase the salability of the merchandise, but to prevent drying out thereof which ordinarily results in loss of profit to the merchant.

What we claim and desire to secure by Letters Patent is:

60 1. In an apparatus of the character described including a support, a track carried by the support, a carriage mounted on the track including primary and secondary frames movable relatively to each other, a motor carried by one of the frames, reversing means mounted on the other frame and operatively connected with the motor, means engaged with said reversing means to effect movement of the carriage along the track, and means connected with the carriage and support 65 for shifting one of the frames relatively to the

other to actuate said reversing means for reciprocating the carriage on the track.

2. In an apparatus of the character described including a support, a track carried by the support, a carriage mounted on the track including primary and secondary frames movable relatively to each other, a motor carried by one of the frames, reversing means mounted on the other frame and operatively connected with the motor, means engaged with said reversing means to effect movement of the carriage along the track, means connected with the carriage and support for shifting one of the frames relatively to the other to actuate said reversing means for reciprocating the carriage on the track, and spray means mounted on the carriage for spraying articles carried by said support.

3. In an apparatus of the character described including a support, a track carried by the support, a carriage mounted on the track including primary and secondary frames movable relatively to each other, a motor carried by one of the frames, reversing means mounted on the other frame and operatively connected with the motor, means engaged with said reversing means to effect movement of the carriage along the track, means connected with the carriage and support for shifting one of the frames relatively to the other to actuate said reversing means for reciprocating the carriage on the track, spray means mounted on the carriage for spraying articles carried by said support, and valve means carried by said spray means and actuated incidental to relative movement of the frames for controlling said spray means.

4. In an apparatus of the character described including a support, a track carried by the support, a carriage mounted on the track including primary and secondary frames movable relatively to each other, a motor carried by one of the frames, reversing means mounted on the other frame and operatively connected with the motor, means engaged with said reversing means to effect movement of the carriage along the track, yieldable means mounted on one of the frames for shifting one of the frames relatively to the other to actuate said reversing means for reciprocating the carriage on the track, and spray means mounted on the carriage for spraying articles carried by said support.

5. In an apparatus of the character described including a support, a track carried by the support, a carriage mounted on the track including primary and secondary frames movable relatively to each other, a motor carried by one of the frames, reversing means mounted on the other frame and operatively connected with the motor, means engaged with said reversing means to effect movement of the carriage along the track, means mounted on one of the frames for shifting one of the frames relatively to the other to actuate said reversing means for reciprocating the carriage on the track, spray means mounted on the carriage for spraying articles carried by said support, means mounted on said spray means and actuatable incidental to relative movement of the frames for controlling said spray means, and air delivery means mounted on the carriage for evaporating a part of the spray collecting on said articles.

6. An apparatus of the character described including a support, a track carried by the support, a carriage mounted on the track, spray means mounted on the carriage, an air delivery means mounted on the carriage, and means

mounted on said carriage and support for moving the carriage along the track for spraying articles carried by the support and for vaporizing a portion of the spray collecting on said articles.

5 7. An apparatus of the character described including a support, a track carried by the support, a carriage mounted on the track, spray means mounted on the carriage, means mounted on said carriage and support for moving the carriage along the track for spraying articles carried by the support, and means mounted on the support and cooperable with the carriage for reversing movement of the carriage on the track.

10 8. An apparatus of the character described including a support, a track carried by the support, a carriage mounted on the track, spray means mounted on the carriage, means mounted on the carriage and cooperable with the support for moving the carriage along the track for spraying articles carried by the support, means mounted on the carriage and support for reversing movement of the carriage on the track, and means mounted on the carriage for rendering said spray means ineffective when the carriage is moved in one direction on the track.

15 9. An apparatus of the character described including a support, a track carried by the support, a carriage mounted on the track, spray means mounted on the carriage, means mounted on the support and carriage for moving the carriage along the track for spraying articles carried by the support, and means mounted on the carriage for intermittently rendering said spray means ineffective.

20 10. In combination with a support, movable means mounted on the support for spraying a liquid upon articles carried by the support, and means mounted on the support and cooperable with said movable means for evaporating a portion of the liquid from said articles.

25 11. In combination with a support, means for spraying a liquid upon articles carried by the support, means carried by said support for evaporating a portion of the liquid from said articles,

30 and means carried by said spraying means and cooperable with said support for intermittently operating said spraying means.

12. In combination with a support, means for spraying a liquid upon articles carried by the support, means carried by the support for evaporating a portion of the liquid from said articles, and means carried by said spraying means and engageable with said support for bodily moving said spraying means along the support.

15 13. In combination with a support, means for spraying a liquid upon articles carried by the support, means carried by said support for evaporating a portion of the liquid from said articles, and means carried by said spray means and engageable with said support for bodily reciprocating said spray means along the support.

18 14. In combination with a support, a carriage movably connected with the support, means mounted on the carriage for spraying a liquid upon articles carried by the support, means mounted on the carriage for evaporating a portion of the liquid from said articles, and means carried by said carriage and cooperable with said support for reciprocating the carriage.

25 15. In an apparatus of the character described including a support, a track carried by the support, a carriage mounted on the track including primary and secondary frames movable relatively to each other, a motor carried by one of the frames, reversing means mounted on the other frame and operatively connected with the motor, means engaged by said reversing means to effect movement of the carriage along the track, means mounted on one of the frames for shifting one of the frames relatively to the other to actuate said reversing means for reciprocating the carriage on the track, spray means mounted on the carriage for spraying articles carried by said support, means mounted on said spray means and actuatable incidental to relative movement of the frames for controlling said spray means, air delivery means mounted on the carriage for evaporating a part of the spray collecting on said articles, and a fan connected with said motor for supplying air to said air delivery means.
